UNITED STATES PATENT OFFICE.

JOSEPH E. PERRAULT, OF WATERTOWN, MASSACHUSETTS, ASSIGNOR TO HOOD RUBBER COMPANY, OF WATERTOWN, MASSACHUSETTS, A CORPORATION OF MASSACHUSETTS.

SOLE-PUNCHING MACHINE.

Application filed July 23, 1923. Serial No. 653,269.

To all whom it may concern:

Be it known that I, JOSEPH E. PERRAULT, a citizen of the United States, and resident of Watertown, in the county of Middlesex, 5 and state of Massachusetts, have invented certain new and useful Improvements in Sole-Punching Machines, of which the following is a specification.

My present invention relates to improvements in punching machines, and aims to provide a machine for punching holes in sole blanks used in the manufacture of rubber soled athletic shoes. In these the soles are provided with recesses which give a 10 suction grip and prevent slipping, and these recesses can be conveniently and economically formed by punching holes completely through the outer sole blanks before they are assembled in the shoe and vulcanized. 15 The unvulcanized rubber of which such sole blanks are formed, is of such a peculiarly plastic and sticky or tacky nature that it cannot be handled in the ordinary type of punching machine, and the present invention 20 aims to provide a machine by which such blanks may be expeditiously and economically punched.

The invention includes the novel features of construction and arrangement and combination of parts hereinafter described, the 25 nature of the invention being defined and ascertained by the claims appended hereto. The invention is shown as embodied in a punching press, in the accompanying drawings, in which:—

Figure 1 is a side elevation of such a press. Fig. 2 is a sectional plan on line 2—2 of Fig. 1.

Fig. 3 is a front view of the die plate and 40 parts carried thereby, and the punch carrying plate, the other press parts being omitted for clearness of illustration.

Figs. 4, 5 and 6 are detailed views. Referring by reference characters to these 45 drawings, the numeral 1 indicates the ram of a punching press, which may be of the ordinary or any desired type and is, therefore, only conventionally shown in the drawings. To this ram is secured a punch carrying plate 2 which carries the punches indicated at 3. In the present embodiment of the invention, the punches are arranged in triplicate, whereby I am enabled to punch the heels and also the balls of the soles of 50 men's, women's and youths' shoes of various

sizes. The punch designated 3^a, Figs. 2 and 3, is for punching a single hole in the heel of a sole blank (indicated at 4), which blank is shown in position in Fig. 2 by dotted lines, as a men's sole blank. The second set 60 comprises four punches indicated at 3^b, which are designed to punch four holes in the ball of the sole blank, and these punches are spaced and disposed for punching the balls of the soles of larger size, such as men's, as 65 indicated by the dotted lines showing the blank and designated 4. The third set of punches indicated at 3^c, comprises four punches disposed in similar relation, but set closer together for punching the balls of the 70 sole blanks used in women's and youths' shoes. There is a wide difference in the sizes of men's shoes on the one hand, and women's and youths', on the other, which requires two sets of punches, 3^b and 3^c, but each 75 class of soles also varies in size according to the size of shoe upon which it is to be used. It is, therefore, desirable to provide means for accurately positioning the various sizes of soles. To this end I provide positioners 80 or gauges, 5^a, 5^b and 5^c, corresponding respectively to the punches 3^a, 3^b and 3^c. These positioners comprise upper and lower carrying plates having recessed front edges, on each 85 side of which recesses are arranged a plurality of stop devices designed to engage with the edges of the sole blank to position it relative to the punches. As each of these stop devices is substantially the same, specific description and detailed illustration of 90 one will answer for all. In Fig. 6, which represents a section on line 6—6 of Fig. 2, it will be seen that the stop device comprises upper and lower plates c, which are secured to a carrying bar 6 located in the rear of the 95 punches and projecting forward therefrom and having their front edges recessed, as indicated at c'. The stop devices are in the shape of rollers c² journaled in the top and bottom plates in two converging rows, as 100 shown. The soles are placed on the die plate and slid forward until the edge of the heel or toe portion contacts with and is positioned by the rollers c², the rolling action of these, by not allowing adhesion to the edge of the plastic sole blank, prevents frictional interference with the placing of the blank. For adjusting the positioners or gauges 5^b and 5^c for varying sizes of soles, the carrying bar 6 105 has one end fulcrumed at 6^a and means are 110

provided by which the opposite end may be moved to determine distances towards or from the punches. Such means, in the present embodiment, takes the form of a spring 5 connecting the free end of the bar 6 to a fixed part of the punch frame, and a swinging handle bar 8 which has a pin or detent 8^a engaging any one of a plurality of notches 9^a in a quadrant plate 9. By swinging the handle to the right direction, the detent may be engaged with one of the notches to hold the bar 6 in position to cause the gauges to position the desired size of sole properly relative to the punches. As the positioner or gauge 5^a cooperates only with the heels, being designed to make a single opening in the heels of both men's, and women's and youths' soles, it requires a different range of adjustment. This is accomplished by securing the positioner plates to an arm 10 fulcrumed at 10^a, which arm is connected by a link 11 with the bar 6.

As hereinbefore stated, the unvulcanized rubber of which the soles are composed is so tacky or sticky that it has a high coefficient of friction to sliding which causes material difficulty in presenting the soles in proper position for punching. Anti-friction devices are, therefore, provided for the surfaces which are touched by the soles, which comprise balls 12 which are placed in holes 13^a in the die plate 13, these holes being constricted at their upper ends so that the balls only project slightly therethrough, as shown in Fig. 5, the balls being inserted from the lower side of the die plate and held in position by suitable closure devices, indicated at 13^b. By reason of the tacky or sticky nature of the rubber, above referred to, means must be provided for preventing the piece punched out by each die from following the punch back through the opening. In the type of die ordinarily heretofore used, the die opening has been made of a size which allows the punched material to pass through with little resistance, the die opening generally being enlarged below the cutting edge. In operating upon resilient tacky material such as rubber, the portion which is punched out remains under compression until the moment of shear, but contracts laterally immediately after the shear, though expanding vertically, and hence barely touches the sides of the die opening, and tends to adhere to the face of the punch and thus be drawn back with the punch. To avoid this, I provide the die opening with a constricted lower part. The die is preferably formed by an inserted thimble 13^x, the upper part of the die opening α of which receives the punch, while the lower part α' is constricted. The result of this is that as the punch forces the punched out piece downwardly, it enters the constricted opening and the lateral pressure caused by the

constricted walls produces a coefficient of friction which is in excess of the tendency of the punched out blank to stick to the face of the punch.

The press is provided with the customary stripper plate, indicated at 14.

Having thus described my invention, what I claim is:—

1. In punching apparatus for the purpose described, a die plate having a die opening, and a reciprocating cylindrical punch cooperating therewith, said die opening having its upper portion corresponding in diameter and length to the die, and having a converging portion immediately below said cylindrical portion. 75

2. In punching apparatus for the purpose described, a reciprocating cylindrical die and a die plate having a die opening therethrough, the upper portion of which opening is cylindrical and of a diameter corresponding to the diameter of the punch while the lower portion is cylindrical and of less diameter, there being an inclined wall portion joining said upper and lower cylindrical portions. 85

3. In apparatus of the class described, a die plate having a die opening, a punch cooperating therewith, guiding means for positioning the articles relative to the punch, and anti-friction devices carried by the die plate adjacent the die opening. 95

4. In apparatus of the class described, a die plate having a die opening, a punch cooperating therewith, guiding means for positioning the articles relative to the punch, and a plurality of balls rotatably seated in recesses in the die plate adjacent said opening, and projecting slightly above the surface of the die plate. 100

5. Sole punching apparatus comprising a die plate having a die opening, a punch cooperating therewith, diverging sole guides arranged on opposite sides of the die opening for engaging opposite edges of the sole, and a plurality of balls rotatably seated in recesses in the die plate between said guides and the die opening, and projecting slightly above the surface of the die plate. 105

6. Sole punching means comprising a die plate having a die opening, a punch cooperating therewith, and positioning means for the sole, comprising a pair of diverging guides, and means for adjusting said guides in unison. 115

7. Sole punching apparatus comprising a die plate having a die opening, a punch cooperating therewith, and positioning means for the sole, comprising two diverging rows of sole engaging members arranged adjacent the die opening and on opposite sides of the path of the punch. 125

8. Sole punching apparatus comprising a die plate having a die opening, a punch cooperating therewith, and positioning means 130

for the sole, comprising two diverging rows of vertically disposed rollers arranged adjacent the die opening and on opposite sides of the path of the punch.

5. 9. Sole punching apparatus comprising a die plate having a die opening, a punch cooperating therewith, and positioning means for the sole, comprising two diverging rows of vertically disposed rollers arranged adjacent the die opening and on opposite sides of the path of the punch, a carrier for said rollers, and means for adjusting said carrier relative to the die opening.

10. 10. Sole punching apparatus, comprising a die plate having a plurality of sets of die openings, a punch plate having punches cooperating therewith, a bar mounted to move towards and from the path of said punches, sole positioning devices carried by said bar, and means for adjusting the position of said bar.

11. Sole punching apparatus, comprising a die plate having a plurality of sets of die openings, a punch plate having punches co-

operating therewith, a bar having one end 25 fulcrumed on a fixed pivot perpendicular to the plane of the die plate, sole positioning devices carried by said bar, and means for adjusting the free end of said bar to predetermined positions.

12. In a sole punching machine, a die plate having a heel and two sets of sole punching means arranged abreast, a die plate having correspondingly arranged die openings, a bar having one end fulcrumed 30 on a fixed pivot and mounted to swing in a plane parallel to said die plate, sole positioning devices carried by said bar for cooperating with said sole punching means, means for adjusting the free end of said 35 bar, an arm fulcrumed on a fixed pivot and carrying a positioning device adjacent said heel punching means, and an operative connection between said arm and said pivoted bar.

In testimony whereof, I affix my signature.

JOSEPH E. PERRAULT.
